PUMP.

No. 903,084.

Specification of Letters Patent.

Patented Nov. 3, 1908.

Application filed February 15, 1908. Serial No. 416,149.

To all whom it may concern:

Be it known that I, CHARLES J. HARTLEY, a citizen of the United States, and resident of Decatur, in the county of Macon and State 5 of Illinois, have invented certain new and useful Improvements in Pumps, of which the following is a specification.

This invention relates to pumps, more especially of that type employing a valved 10 reciprocating piston; and the object of the same is to permit the adjustment of the head and its parts rotatably with relation to the pump body and support.

To this end the invention consists in an 15 improved construction of several parts of the pump, as hereinafter more fully described and claimed and as shown in the drawings in which—

Figure 1 is a central vertical section of the 20 entire device. Fig. 2 is a plan view showing the spout or spouts, part of the flange of the head being broken away.

In said drawings the reference numeral 1 designates the supply pipe threaded into the 25 lower end 2 of the pump body which comprises a cylinder 3 containing a piston 4 valved as at 10, upper and lower flanges 5 and 6 which may be integral with but are here shown as screwed around the cylinder 30 near its extremities, connections such as bolts 7 between the lower flange 6 and the lower end 2, packing 8 between these elements carrying an inlet valve 9, and a head. The latter as herein shown comprises a cap 32 having a flange 33 containing a stuffing 35 box 31 in which is mounted a gland nut 30. The numeral 39 in Fig. 1 designates the inner end of the spout leading out of the cap, and in Fig. 2 391 designates its outer end to

40 which a suitable nozzle is to be attached. It is possible that another spout 392 could open radially from some other point within the head, but if two or more spouts are employed all but that one to which the nozzle is attached should be closed by plugs 393. The piston is moved by a yoke 11 at the lower end of a pump rod or stem 12 which passes through the gland nut and is connected with a handle 13, the latter being connected by a pivotal 45 link 40 with an ear 41 rigidly supported by the head, and hence the adjustment of the latter with relation to the pump body will adjust the position of the handle as well as that of the spout. It is possible, as shown,

to form the ear as part of a collar 42 loosely 55 surrounding the stuffing box 31 and resting on the body of the cap 32—some such means as a set screw 43 being employed for holding the collar after it has been adjusted. This would permit the handle and its support to 60 be rotatably adjusted with respect to the head, independent of the adjustment of the latter with respect to the pump body.

While any suitable means may be employed for connecting the cap and body, permitting their relative adjustment, and holding them after they are adjusted, I prefer that shown herein and which will now be described. The upper flange 5 is provided with a dove-tailed or inverted T-shaped angular groove 34, illustrated in section in Fig. 1 and in plan view in Fig. 2, and at points within this groove are openings 35 leading from its larger lower portion upward through the top face of the flange. Into these openings may be dropped the heads 36 of bolts 37 whose shanks pass through holes in the flange 33 to receive exposed nuts 38. By this construction it will be seen that on loosening the nuts 38 the entire head can be rotatably 75 adjusted upon the body of the pump so as to cause any spout that is in use to occupy the desired position over the sink or with relation to the support and the wall, after which the nuts are tightened up to clamp the head 80 to the body of the pump. Also it will be clear that by turning the former on the latter until the heads 36 of the bolts 37 come under the openings 35 (which occur at points where it probably never would be desirable to 85 tighten up the bolts) the head can be detached as for cleansing or repair of parts.

While any suitable means may be employed for supporting the body of a pump having substantially the construction above 95 set forth, I prefer that herein illustrated and which will now be described: Projecting radially from the flanges 5 and 6 are nipples 20 internally threaded and exteriorly shouldered as at 21. 22 is the upright body of a 100 bracket which may be attached to a vertical wall as by screws taking through its ears 23, and projecting from this body are tubes 24 whose outer ends are adapted to receive said nipples 20 and abut against their shoulders 105 21. The inner ends of the tubes are counter-bored as at 25 to receive washers 26 and the heads 27 of bolts or screws 28, which latter

are of a length to reach through the tubes and detachably engage with the threads in the nipples 20—all as seen in Fig. 1. By this construction it is possible to support the 5 pump from a wall or other upright, instead of from a base as so common at the present time; and hence the pump body may be located adjacent or over a sink, and all that necessarily depends from it is the supply pipe 10 1 which in fact might be curved so as to lead through the wall of the sink or over its edge—thus leaving the space beneath the sink entirely clear.

It will be obvious that the pump body can 15 be detached from the bracket and the latter removed from its support at any time, as for repair or substitution of parts. However, it is not essential to the successful operation of the pump herein described that this support 20 shall be employed, or, if it is used, that its parts shall be detachable from each other, for it is obvious that the head or handle or both could be rotatably adjusted on the body whatever the form of the support.

25 Many other details are susceptible to considerable variation and amplification which may well be left to the manufacturer.

What is claimed as new is:

1. In a pump, the combination with the 30 body, flanges surrounding it, and nipples projecting radially therefrom; of the head carrying a spout, the handle mounted on the head, and means for permitting the rotary adjustment of said head and handle on said 35 body.

2. In a pump, the combination with the body, flanges surrounding it, nipples projecting radially therefrom, a bracket secured 40 to an upright support, and screws leading through the bracket and taking into said nipples; of the head carrying a spout, the handle mounted on the head, and means for permitting the rotary adjustment of said head and handle on said body.

45 3. In a pump, the combination with the body including a cylinder and a surrounding flange containing an inverted T-shaped annular groove opening through its top face, and a radial support for said flange; of a cap 50 having a flange registering with that of the body, bolts whose heads lie in the larger portion of said groove and whose shanks pass

through said cap-flange with their nuts exposed, and a piston, stem, and handle.

4. In a pump, the combination with the 55 body including a cylinder and a surrounding flange containing an inverted T-shaped annular groove opening through its top face, openings of the size of the larger portion of this groove extending also through said top 60 face at certain points, and a radial support for said flange; of a cap having a flange registering with that of the body, bolts whose heads are adapted to pass through said openings and lie in the larger portion of said groove 65 and whose shanks pass through said cap-flange with their nuts exposed, and a piston, stem, and handle.

5. In a pump, the combination with the 70 body including a cylinder and a surrounding flange containing an inverted T-shaped annular groove opening through its top face, and a radial support for said flange; of a cap having a flange registering with that of the body, bolts whose heads lie in the larger portion 75 of said groove and whose shanks pass through said cap-flange with their nuts exposed, a stuffing box on said cap, a collar rotatably mounted on said box and carrying the handle-support, and a piston, stem, and 80 handle.

6. In a pump, the combination with the body including a cylinder and a surrounding flange containing an inverted T-shaped annular groove opening through its top face, 85 openings of the size of the larger portion of this groove extending also through said top face at certain points, and a radial support for said flange of a cap having a flange registering with that of the body, bolts whose 90 heads are adapted to pass through said openings and lie in the larger portion of said groove and whose shanks pass through said cap-flange with their nuts exposed, a stuffing box on said cap, a collar rotatably mounted 95 on said box and carrying the handle-support, and a piston, stem, and handle.

In testimony whereof I sign my name in the presence of two subscribing witnesses, this the eleventh day of February, 1908.

CHARLES J. HARTLEY.
